UNITED STATES PATENT OFFICE.

ROBERT L. CARR, OF FALL RIVER, MASSACHUSETTS.

APPARATUS FOR REWINDING YARN FROM BROKEN OR DAMAGED COPS.

SPECIFICATION forming part of Letters Patent No. 276,668, dated May 1, 1883.

Application filed March 7, 1881. (No model.)

To all whom it may concern:

Be it known that I, ROBERT L. CARR, of Fall River, in the county of Bristol and State of Massachusetts, have invented a certain new and useful Apparatus for Rewinding Yarn from Broken or Damaged Cops; and I do hereby declare that the following specification, taken in connection with the drawings furnished and forming a part thereof, is a clear, true, and complete description of my invention.

My invention relates to means for the utilization of broken or imperfect mule cops, which have always heretofore been considered waste, because the yarn could not be properly delivered therefrom during the flight of the shuttle in weaving. Frequently a cop is rendered of little value by careless handling while removing it from the mule-spindle, and when only partially damaged or broken some portions of it are sometimes used in weaving or spooling, the remainder being thrown aside as "waste," usually in a tangled mass. In spooling off mule-cops of warp-yarns the yarn is usually drawn from the cops while the latter are firmly mounted on fixed spindles, and as the delivery of yarn from the cops in such case is substantially like the delivery from a cop in a shuttle, the same difficulty is encountered as in weaving, although to a lesser degree and resultant of a lesser proportion of cop-waste than is attendant upon weaving. The loss of time by the weaver and his looms incident to bad cops in the shuttle, and the faulty cloth liable to result therefrom, are strongly conducive to the rejection by the weaver of all but apparently perfect cops. The shrinkage in yarn apparent from a comparison of the gross product of a mule-room with the net consumption thereof, as evidenced by the woven product, is well known to be a serious item of loss in all mills, and the portion of said shrinkage treated as merchantable waste is well known to be far below the actual quantity to be accounted for after deducting the yarn actually worked in the looms. The well-known disposition on the part of weavers and spoolers to conceal the results of their careless handling of cops leads to the wrongful concealment and practical destruction of a good proportion of the broken or damaged cops rather than expose themselves to possible cen-

sure. So far as my knowledge extends, this mule-cop waste has heretofore been almost wholly utilized as "wiping" waste for cleaning machinery, and subsequently thereto as paper-stock. It has, however, been proposed to mechanically restore the fiber of such waste to a separated condition, from which it may be respun; but, so far as my knowledge extends, the fiber is thereby so cut and torn as to render yarn made in whole or in part therefrom of comparatively little value.

The value of "cop-waste" as a merchantable article for wiping purposes does not bear a fixed proportion to the original value of the yarn therein, but it ranges only in accordance with the varying value of the original fiber—as, for instance, print-cloth cop-waste would be valued per pound at about one-quarter of the value of the yarn, (whatever the value of the cotton might be,) while cop-waste of more expensive yarns from mills producing finer goods the proportion of value would range from one-eighth upward.

The object of my invention is to utilize such cop-waste for the purposes for which the yarn was originally intended without in any appreciable manner detracting from its value by injury to the fiber, and to reduce the proportion of waste hitherto wrongfully diverted and absolutely lost to the manufacturer.

It has heretofore been proposed to rewind imperfect cops by the use of apparatus illustrated in English Letters Patent No. 2,979 of A. D. 1863, embodying winding mechanism, in combination with unwinding-spindles having rigid foot and head bearings; but I have found that the unwinding of imperfect cops cannot be practically accomplished unless the unwinding-spindle be capable of yielding under the tension of the yarn, in order that the spindle may, by assuming slightly-varying angles with relation to the line of yarn as it is drawn from the cop, enable the yarn to free itself from the "mats" or "snarls" common to broken or imperfect cops; and my invention consists mainly in the combination, with winding mechanism, of an unwinding-spindle which is capable of being bodily moved or deflected by the tension of the cop-yarn during the unwinding of the same from said spindle. This capacity in the spindle may be provided for in various

ways—as, for instance, by means of a limited step-bearing and a yielding head-bearing, or by the flexibility of the spindle itself, or by permitting the spindle to be lifted bodily by the yarn. For thus rewinding and obtaining the most economical results, a change of system is advisable in the weave-room and the spool-room, under which each weaver and spooler-tender is provided with a box, into which all imperfect cops and parts of cops are to be carefully deposited from time to time, as they come to hand in the process of weaving or spooling, instead of permitting such cops to be further broken and torn into a tangled mass, as is now the universal practice.

Although spindles backwardly rotated by the draft of the yarn are preferable for obtaining the best results, provided said spindles be capable of moving bodily at one or both ends, as before stated, the well-known cop-warp spooler hereinbefore referred to may be made fairly serviceable for my purposes, if it be modified and changed in construction as follows: By making the spindles light and rotative instead of fixed, or, if fixed, reducing the diameter of such spindles to such an extent as to render them flexible, and also permit a broken cop to rotate freely thereon, and in either case providing for sufficient free bodily movement of the upper ends of the spindles to allow for a change in position while the yarn is unwinding from a break or snarl, and arranging for the draft on the yarn in a line nearly or practically at right angles to the axes of the broken cop, instead of, as now in such machines, drawing off the yarn in a line practically parallel or coincident with said axis. I hereinafter describe, and illustrate in the drawings, various types of mechanism whereby the prime objects of my invention may be obtained. Broadly stated, such mechanism must involve suitable winding mechanism, in combination with a light unwinding-spindle which is susceptible of axially entering or piercing a broken cop, is either capable of rotation with the cop or freely permitting the latter to rotate thereon under the unwinding tension of the yarn, and is also movable bodily at one or both ends under the tension of the yarn in unwinding, so that when the delivery thereof is obstructed by a mat or snarl in the cop the spindle can slightly change its position with relation to the line of draft on the yarn leading therefrom, thus enabling the latter to free itself in unwinding. While it is preferable that the unwinding-spindle shall occupy a truly central position in the cop, the yarn may be, nevertheless, withdrawn from such badly-broken cops as are not truly concentric with the spindle. The character of the winding mechanism should of course be adapted to the use to which the recovered yarn is to be applied. If to be used as a spoolless cop within a shuttle, the winding mechanism would involve a spindle like that of a mule, and a traverse motion, which, as in a mule, will properly lay the yarn and build up the cop. If the recovered yarn

is to be used as warps, the usual spool and traverse motion will serve the purpose; or the yarn may be unwound from the broken cop directly upon a swift or reel to be rewound therefrom or removed in hanks. If the recovered yarn is to be used as a spooled cop for shuttles, it may be wound as in the well-known "quiller," or upon a spindle like that of a mule.

The several features of my invention will be specified in detail in the claims hereunto annexed.

Referring to the drawings, Figure 1 represents in vertical lateral section so much of a machine as will illustrate my invention when the recovered yarn is to be placed on spools or quills for use in shuttles. Fig. 2 is a similar view illustrating the spooling of the recovered yarn, as for warps. Fig. 3 is a similar view illustrating the reeling of the recovered yarn. Fig. 4 is a similar view illustrating the copping of the recovered yarn into the same form originally occupied by it upon the mule-spindle. Fig. 5 is a similar view illustrating the reeling of the recovered yarn from a broken cop mounted upon an unwinding-spindle, which is free to rise and fall with the varying tension on the yarn incident to the varying freedom of delivery from a broken cop. Fig. 6 is a plan view of a yielding top bearing for the unwinding-spindle.

In connection with all of these figures it is to be understood that the mechanism for winding therein shown contains no novel features, and that I shall deem it only necessary to describe the same so far as will show their mode of operation with the unwinding-spindles when combined therewith in accordance with my invention. On each of the organizations shown the unwinding-spindle A, as constructed and applied, is a novel element. The upper portion of a mule-spindle may be readily converted into one suited for this purpose. The rotating spindle is provided with a step, a, and yielding head-bearing b, as indicated in Figs. 1, 3, and 4, in which case the spindle and broken cop c are rotated together in unwinding; or the spindle may be fixedly mounted, as in Fig. 2, in which case it is made still smaller in diameter, so as to permit the broken cop c to rotate freely thereon in unwinding. This form of spindle should be very light, so as to be flexible under tension of the yarn, and if not it should be flexibly mounted at its base and provided with a yielding top support to admit of the desirable bodily movement of the upper end of the spindle; or the spindle may be arranged, as in Fig. 5, so that the broken cop may freely revolve on the spindle, or the cop and spindle revolve together, as the varying condition of the broken cop may require for the proper delivery of the yarn in unwinding. In this case the two ends of the spindle are free and occupy slots d in a pair of parallel inclined standards, e, which permit the spindle to rise or fall under the varying tension of the yarn. The inclined slot, when the spindle is lifted, is conducive to the rotation of the

spindle, and thus aids in the free delivery of the yarn from the broken cop *c*. A light spring, *f*, may be relied upon for properly controlling the lifting of the spindle, and the end 5 guides, *g*, for preventing its undue endwise movement. In all cases I deem it absolutely essential that the upper or head bearing, *b*, of the unwinding-spindle be slightly yielding, and this can be provided for in various ways, 10 as illustrated, for instance, in Fig. 6, the light spring *h* having an abutment or bearing, *h'*, at its free end, with which the upper end of the spindle engages whenever the tension on the yarn in working free from a snarl or 15 break is sufficient to require this yielding effect. The yielding head-bearing *b* used with the rotary spindle may be made of spring metal, so as to enable their outer ends to be lifted for the insertion of the top of the unwinding-spindle; or said head-bearing may be 20 made heavy, and hinged, as indicated in Fig. 6, so as to be held down at its outer end by its own weight.

I am aware that it is common in bobbin-winding machines to pivotally mount the cop-receiving spindles to a rail, so that they may be turned down for receiving a cop, and then turned upward, so that the yarn may be drawn off over the end of the cop without rotation, 25 as illustrated in the United States Patent No. 6,435, May 8, 1849.

Although good results may be attained with rotating metallic spindles for receiving the broken cops, I generally prefer that they be 30 composed of light hard wood. Such wooden spindles may be used with a bone or ivory step. For rendering the wooden spindles more durable they may be provided with light metallic tips.

40 Referring now to Fig. 1, it will be understood that the winding-spindle *B* is of the type employed in quillers, but driven at a slower speed than heretofore, and that as the yarn is laid upon the bobbin *i* the latter rises, as indicated in dotted lines, until the foot of the spindle is lifted from its driver *k*. These spindles have been heretofore used in combination with reels or swifts located below the spindle, and upon which yarn in hanks has 45 been placed.

In Fig. 2 the winding-spindle *E* is as heretofore used for driving spools; but it should be driven at comparatively slow speed, because the broken cop *c* in this case rotates wholly independent of the unwinding-spindle.

55 In Fig. 3 the reel *C* is of the ordinary type, but should be driven much slower than is usual in reeling, because the delivery of yarn from the broken cop *c* is of necessity a much slower 60 operation than when reeling from well-laid bobbins.

In Fig. 4 the winding-spindle *D* is of the

usual type used in "mules;" but it is of course driven at such slow speed as will best take off the yarn from the broken cop *c*, and therewith 65 is used a traverse or copping motion similar to that used in mules, except that it is continuous in its reciprocatory operation instead of intermittent.

In Fig. 5 the reel *F* is of the simplest type, 70 and with this, as well as that shown in Fig. 3, a lateral traverse motion may or may not be used.

When a long slender rotating unwinding-spindle is employed I sometimes furnish it 75 with a steadyng-bearing for the spindle at a point below the cop, as shown at *m* in Fig. 1, for guarding against such a bending of the spindle as would render it less liable to freely rotate. The step and head bearings of a rotary spindle should both be of such a character as will be conducive to a minimum of friction between them and the spindle.

As regards the stationary unwinding-spindle *A* in Fig. 2, it will be understood that I 85 prefer to employ at all times a spindle which can rotate; and I am well aware that if my unwinding-spindles be applied to machines for spooling mule-cop warps the quantity of warp-cop waste will be greatly reduced as compared with the quantity resulting from the 90 practice of the present common methods. I do not maintain that the yarn of cop-waste can be wholly devoted to its original purposes by the practice of my invention; but if properly worked not more than ten or fifteen per cent. of the waste heretofore resulting need be sold as wiping-waste, and the cost of recovery 95 under my invention of the remainder will seldom, if ever, exceed fifteen per cent. of its value. 100

Having thus described my invention, I claim as new and desire to secure by Letters Patent—

1. The combination, with yarn-winding mechanism, of an unwinding-spindle which is capable of bodily movement under the tension of 105 yarn from a cop carried by said spindle, substantially as described, whereby in unwinding a broken or imperfect cop said spindle may slightly change its position with relation to the line of the yarn leading therefrom, and thereby enable the yarn to free itself from a mat or snarl in the cop, as set forth.

2. The combination, with yarn-winding mechanism, of an unwinding-spindle rotatively mounted, and a yielding head-bearing for said 115 spindle which permits the latter to be deflected under the tension of yarn drawn from a cop mounted on said spindle, substantially as described.
